UNITED STATES PATENT OFFICE

CLYDE S. MORSE, OF DE KALB, ILLINOIS

DESIGN FOR A DRINK-MIXER STANDARD

Application filed February 24, 1930. Serial No. 34,639. Term of patent 3½ years.

To all whom it may concern:

Be it known that I, CLYDE S. MORSE, a citizen of the United States, residing at De Kalb, in the county of De Kalb and State of Illinois, have invented a new, original, and ornamental Design for a Drink-Mixer Standard, of which the following is a specification, reference being had to the accompanying drawing, forming a part thereof, in which the figure is a perspective view of the article illustrating my new design.

I claim:

The ornamental design for a drink-mixer standard substantially as shown.

CLYDE S. MORSE.
